UNITED STATES PATENT OFFICE.

BARSAM S. BARSAMIAN, OF DETROIT, MICHIGAN.

DESIGN FOR A SHOE.

51,407.

Specification for Design.

Patented Oct. 23, 1917.

Application filed August 3, 1917. Serial No. 184,335. Term of patent 14 years.

To all whom it may concern:

Be it known that I, BARSAM S. BARSAMIAN, a subject of the Sultan of Turkey, residing at Detroit, in the county of Wayne and State of Michigan, have invented a new, original, and ornamental Design for Shoes, of which the following is a specification, reference being had to the accompanying drawings, forming part thereof.

Fig. 2 is a front perspective of the shoe.

I claim:—

The ornamental design for a shoe, as shown.

BARSAM S. BARSAMIAN.
